Specification for Design.

Patented Apr. 2, 1918.

Application filed December 21, 1917. Serial No. 208,327. Term of patent 7 years.

To all whom it may concern:

Be it known that I, JOHN L. FLANNERY, Jr., a citizen of the United States, residing at Chicago, county of Cook, and State of Illinois, have invented a new, original, and ornamental Design for an Envelop, of which the following is a specification, reference being had to the accompanying drawing, forming a part hereof.

Figure 1 is a plan view of an envelop, in accordance with the design; and Fig. 2 is a cross-sectional view, each line indicating a thickness of paper.

I claim:

The ornamental design for an envelop, as shown.

JOHN L. FLANNERY, JR.
